FEEDING MEANS FOR TAPE

Trevor R. Gautier, Nashua, N. H., assignor to
 Nashua Gummed and Coated Paper Company,
 Nashua, N. H., a corporation of Massachusetts

Application October 31, 1939, Serial No. 302,199

2 Claims. (Cl. 271—2.1)

My present invention relates to serving or dispensing strip material such as adhesive tape, labels and the like, especially dry gummed tape. More particularly, it aims to provide improved feeding means for such material in association with machines or devices for serving or delivering moistened lengths of the material from a supply thereof, for sealing, packaging, labeling and kindred purposes.

As to all common subject matter this application is a continuation of my copending application, Serial No. 142,668, filed May 14, 1937.

In the drawing illustrating by way of example certain embodiments of the invention:

Fig. 1 is a longitudinal vertical section of a portion of a strip server or tape dispenser equipped with feeding means in accordance with one form of the invention;

Fig. 2 is a top plan of the feeding means or assembling unit of Fig. 1;

Figs. 3, 4 and 5 illustrate another embodiment of a feed assembly corresponding to that of Figs. 1 and 2, Fig. 3 being a top plan, Fig. 4 a longitudinal vertical section through the unit of Fig. 3 and Fig. 5 a bottom plan;

Figs. 6 and 7 show a further modification of such feed assembly in accordance with the invention, said figures corresponding to Figs. 3 and 4 respectively; and

Figs. 8 and 9 show still a further form of the invention, said figures being respectively a top plan and a vertical longitudinal section similarly as in Figs. 6 and 7.

Referring to the drawing in more detail, Fig. 1 illustrates one form of the tape feeding and guiding means, with which the invention is particularly concerned, in connection with a strip server or tape dispenser of the hand type suitable for use on store counters, at package wrapping stations, in shipping rooms and such locations. In various respects, however, the invention is adapted for use with other than manual dispensers, including the semi-automatic and automatic types of such machines.

The illustrative machine of Fig. 1 comprises a frame or housing including side walls, one of which is indicated at 1, a front wall 2, a rear wall (not shown) and an intermediate wall 3. The latter defines two main compartments for the machine, a rear compartment 4 providing a support, housing or well for the tape supply a roll R, and a front compartment 5 forming a tank or reservoir for the moistening liquid. The frame further includes a bottom wall 6, the forward portion of which forms the bottom for

said reservoir, and a rear portion thereof acting to support the tape supply R. One or more guide rollers, such as indicated at 7, may be disposed transversely in the tape well 4, to assist in positioning the roll of tape for feeding.

The machine is equipped with means associated with the liquid reservoir 5 for moistening the gummed underface of the tape T coming from the roll supply. In the illustrated example 10 such means comprises a capillary moistening element or brush 8 set in the reservoir and projecting upwardly at the front or delivery portion of the machine into the path of the tape so as to have moistening engagement with its underface as it issues from the machine. One or more positioning lugs 9 in the reservoir retain the moistener 8 in proper operative position. The rear wall 3 of the reservoir is apertured at its upper part as at 3a to limit the height of the liquid to a level below the tape feeding and guiding means now to be described.

Such means, through the medium of which the tape T from the supply R is adapted to be advanced for delivery in moistened condition at 25 the front end of the machine, comprises a feed and guide assembly or unit, sometimes herein referred to as the feed-guide plate or tape chute. Said assembly is disposed, preferably removably, at the top of the front compartment or reservoir 30 5, providing in effect a cover for the latter as well as a tape-guiding floor bridging across between the tape roll compartment 4 and the delivery station adjacent the moistener 8.

In the embodiment shown in Figs. 1 and 2, this 35 feed-guide assembly comprises a bottom plate floor, or under guide element 10 and an overlying top plate or upper guide element 11, spaced from the bottom plate as by side flanges 12, said elements together defining a feed throat or chute 40 for the tape. Said under guide or floor element 10 and the upper and lateral guide means 11, 12 may be separably related and held in assembled position, and in place on the machine frame, as by clips or the like on either or both of them. 45 As here shown, however, said parts are attached together, as by interlocking formations such as the down projections 13 on the side walls 12 of the upper plate received in corresponding openings 14 in the bottom plate 10, their projecting ends being turned to prevent their unintentional withdrawal, in some such manner as seen in Fig. 5.

The feed-guide assembly as a whole is operatively positioned on the machine frame, as upon 50 the frame side walls 1. The latter may be re-

cessed along their inner top edges to provide shoulders for receiving the opposite side edges of the bottom plate 10 further to position the assembly unit.

At its rear end the bottom plate 10 desirably has a down-turned lip 15 to receive the tape coming from the roll R. Extensions of said lip may be formed as open bearings or hinge fingers 16 cooperable with studs 17 on the inner faces of the opposite side walls 1, additionally to position the feed-guide plate or assembly with capacity for upward swinging or bodily removal. At its fore end the bottom plate 10 may be upturned as at 18 to assist in directing the tape accurately up to and across the moistener 8. The front edge of the upper plate 11, adjacent the moistening and delivery station, is constructed and arranged to form a severing element or cutter 19 for the tape. Said upper plate desirably also has its rear end turned up as indicated at 20 to assist in guiding the tape into the feed chute, particularly in instances where the tape is overfed, that is, from the top of a roll supply wound gummed side in. The tape T as indicated in dotted line in Fig. 1 is underfed, that is, from the bottom of the roll supply R which is assumed to be wound with the gummed face out. It is also to be noted that the oppositely deflected rear end portions or lips 15 and 20 of the bottom and top plate elements 10 and 11 form in effect a receiving throat into which the leading end of the tape is easily threaded, in initially setting up the machine or when installing a fresh roll of tape.

From the foregoing it will be seen that the feed-guide assembly or tape chute comprises a flooring or floor element including the bottom plate 10 underlying and defining a path for the tape, together with suitable guide means at the sides of and above the tape path to confine the advancing tape to the latter. Such guide means is herein afforded by the top plate guide 11, which is longitudinally apertured or open for a substantial portion of its length, as indicated at 21, to expose the tape path. This top opening permits the upper face of the tape to be engaged, either by one or more of the operator's fingers or by an appropriate presser device, to move the tape forwardly along its path as defined by the underlying floor.

Referring now especially to Figs. 1 and 2, the bottom plate 10 of the flooring is formed with a longitudinal slot formation 22, rearwardly of its front or tape delivery end and extending back toward the roll supply. The term "slot" is here to include a formation in the nature of a depression or recess with closed or partly closed bottom, and also a cut-out, aperture or through-opening formation. At least a portion of this slot formation 22 in the under guide 10 lies vertically opposite the top opening 21 of the upper guide means.

In the space thus afforded I provide a supplemental movable flooring or tape-supporting floor means adapted to have supporting engagement with the underface of the tape and to move in synchrony with the latter as the tape is advanced or fed forwardly for delivery. It will be understood that the tape is advanced by the operator, in the case of the manual machines such as herein shown, by placing his finger, or a number of fingers, on the exposed top face of the tape, over the movable flooring means, and moving his finger toward the front of the machine while pressing downwardly sufficiently to cause the tape and the underlying movable feeding and

guiding or flooring elements to be moved with and by his fingers.

In the embodiment of Figs. 1 and 2 such movable flooring means comprises a plurality of rotary elements or roller-like units, four of which are seen in Figs. 1 and 2, respectively, indicated as a whole by the numerals 25, 26, 27, 28. Said elements are rotatably mounted in the slot formation 22 with their upper portions or crests in or slightly above the plane of the tape path as defined by the cooperating floor plate 10. In this instance said plate 10 has down-turned portions 10a at the sides of the slot formation 22 providing hanger means or flanges in which the movable floor elements 25 to 28 are rotatably held at their opposite ends.

These rotary flooring elements individually may be variously constructed and arranged as appropriate for different service conditions. In the example illustrated the two foremost elements 25 and 26 are each integrally formed in one piece. Each comprises a plurality of laterally spaced circumferential ribs or disks 29, with intermediate spacer portions 30 of reduced diameter, and end bearings or pintles 31 received in said flanges 10a of the plate 10. The adjacent rotary elements 25 and 26 are disposed with their disk parts 29 in spaced or non-overlapping, non-intermeshing relation lengthwise the tape path, this same condition preferably applying whether the disk parts 29 are arranged in alignment lengthwise the tape path or are offset or staggered as in the elements 27 and 28.

One alternate construction for such rotatively movable flooring elements or units is represented in the element 27. As seen in Fig. 2, this element comprises a shaft 32 mounted in the flanges 10a and having concentrically disposed upon it alternating disks 33 and spacers 34. Said parts 33 and 34 may be fixed on the shaft, the latter being rotatable in its bearing flanges, or said parts may be loosely disposed on the shaft for rotation individually and independently of the latter.

In other instances the construction may be as in the rotary element or unit 28, comprising a supporting shaft 35 hung on the flanges 10a and having distributed along it a plurality of separate sleeve-like parts, some of which have in one integral piece a flange or disk portion 36 and, at least at one face of the latter, a spacer portion 37 of reduced diameter. One spacer portion 37 is disposed between each disk member 36. The individual sleeve-like elements may consist of one disk 36 and one integral spacer 37, as at the upper right portion in Fig. 2, or they may have integral spacers 37 at both sides, as at the lower right corner in Fig. 2. Plain disk elements, such as represented at 36a may be interposed at appropriate points to make up the rotary element 28 as a whole, with the laterally spaced disks 36 or 36a coming at the desired locations crosswise of the tape path. As in the instance of the element 27 the parts or sub-units 36, 36a, 37 of the element 28 may be either fast or loose on their supporting shaft 35.

The flange or disk members of the adjacent rotary elements, whether of the type of the unit 27 or the unit 28 are all disposed, in the illustrated example, in non-intermeshing relation in succeeding rows. They may be mutually offset substantially as illustrated, or may be in alignment lengthwise the tape path, as in the case of the disks of the units 25 and 26. That is, in any adjoining disk-rows or rotary elements 25, 26, 27

or 28, the disk or flange parts having the larger diameter may either be offset or in line with each other lengthwise the tape chute. In general, the built-up form of rotary element such as 27 or 28 is especially adapted for use at the rear portion of the feed-guide, where the capacity of the individual parts to shift in the axial direction is of assistance in supporting or aligning the tape laterally of the guide as a whole. Conversely, the integral elements such as 25 and 26 are especially suitable at forward locations. Such integral or solid units 25, 26 by reason of their greater mass have a somewhat greater inertia, tending to oppose undesired forward movement of the tape from its rest position and, at the end of a feeding movement, to advance the leading end of the tape slightly beyond the delivery end of the chute.

Turning now to Figs. 3 to 5, any parts therein not otherwise referred to may be the same as in Figs. 1 and 2. In this instance the guide flooring or underplate 40 has a similar slot formation 42, with depending flanges 40a at its opposite side portions. Mounted on side flanges is a plurality of roller bearing elements 43 held against axial displacement as by cotter pins or the like 44; see Fig. 5. Said bearings 43 support a longitudinally movable feed element or feed slide 45 comprising a body or main slide of a length exceeding that of the slot formation 42, so as to cover the latter, at least in the rear or normal stationary position of the slide, as shown in Figs. 3 to 5.

On the upper face of the slide 45 is an upstanding projection or cross piece 46, the rear edge of which is adapted to abut the back edge of the slot formation 42 as a stop. Said cross piece 46 is desirably roughened at its top face for firm engagement with the tape or has attached to it a tape-engaging element 47, secured by rivets or the like 48, Fig. 3. Said engaging member 47 may be corrugated, fluted or otherwise formed as indicated at 49 to facilitate its non-slip engagement with the under gummed face of the tape when the latter is pressed down onto it for a feeding operation.

The feeder slide 45 as a whole is normally held rearwardly in, and is returned to, its inactive position in readiness for the next feeding action. Suitable spring means is provided for this purpose, such as the coil spring 50 anchored at its rear end to the depending rear flange portion 40b of the floor plate 40 and at its front end connected to a finger 51 on the feed slider.

In the further modification illustrated in Figs. 6 and 7 parts not otherwise referred to may again be as in previous figures, this also applying in connection with Figs. 8 and 9. The under guide or flooring plate 60, Figs. 6 and 7, has a slot formation 61, in this instance in the nature of a depression or recess closed or partly closed by the depressed bottom-forming element or plate 62 supported between and by the depending flanges 60a at the sides of the slot formation 61. This auxiliary plate 62 serves in part as a supporting guide for one or more endless conveyor elements, flexible travelling bands or the like 65. Two of such endless movable elements are here shown, one to each side of the longitudinal center line of the tape path. In the particular example illustrated said elements are formed of a multiplicity of hingedly interconnected links 65a. The upper run of each such element is guided along and upon the supporting plate 62, the latter preferably having longitudinal ribs or the like 62a

to assist in guiding the endless feeder elements 65 in their feeding movement. At the rear said longitudinally movable feeders are supported and guided around a roller or the like 66, and at the front they are similarly guided as upon arcuate flange 67 depending at the front edge of the supporting plate 62.

It will be understood that the desired length of tape is fed by the operator, by depressing the tape against the endless feeder device at any appropriate point lengthwise the feed-guide as a whole, and moving the tape together with one or more endless travelling elements of said device in a generally similar manner as in the other figures.

In the further modification of Figs. 8 and 9 the movable flooring means for assisting in guiding and feeding the tape comprises a plurality of individually rotatable but axially fixed roller elements, somewhat as in Figs. 1 and 2. In this instance, however, the flooring plate 70, apertured at 71 and similarly provided with depending side flanges 70a, carries a plurality of cylindrical feed rollers of which one or more differ from others in diameter. As shown in said Figs. 8 and 9, two rolls 72 and 73 are each of the same or similar and relatively large diameter and are rotatable on or rotatably supported by axial members 74 and 75 respectively, received in the depending flanges 70a. Between said larger rollers 72 and 73 and in a spaced relation so as to be out of contact with them is a roller 76 of relatively smaller diameter and having supporting axial means 77. In this series of rollers 72, 73, 76 alternately of relatively large and relatively small diameter individually, the several rollers are so disposed that their upper portions or crests are in or slightly above the plane of the tape path as defined by the flooring plate 70. It will be understood that the several rollers of such series may be otherwise arranged than as illustrated, as by interposing one larger roll between two smaller ones. In general it is preferable to locate one of the smaller rollers between each two of the larger ones, but in the case of longer guides two or more of the larger diameter rolls, or two or more of the smaller ones, may be juxtaposed at one or more positions lengthwise the feed-guide means as a whole.

My invention is not limited to the particular embodiments herein illustrated or described, and I set out its scope in my following claims.

I claim:

1. In a gummed tape dispenser comprising a frame having a support for a tape supply and a forward tape delivery portion, feed guide means associated with said forward portion, said means comprising an assembly unit including a bottom plate having a longitudinal slot formation, a separately formed top plate also having a slot formation opposite that in the bottom plate, said top plate being of less width than the bottom plate and having downturned side flanges for supporting and vertically spacing it above the latter and providing side guides for the tape to be advanced between the two plates as a feed throat, said plates having interlocked projections and receiving formations for attaching them in assembled relation, the front ends of the plates being vertically deflected in substantial parallelism for tape directing purposes and their rear ends being deflected away from each other to form a receiving mouth at the rear of the feed throat, said rear deflected portion of the bottom plate adapted to aid in positioning the assembly unit on the

dispenser frame with capacity for upward swinging about its rear portion and for bodily removal and the frame having laterally extending positioning means for cooperation with said rear portion of the bottom plate to afford it said capacity, and movable flooring means operatively disposed in said slot formation of the bottom plate and comprising a plurality of rows of rotary disk elements, the latter being laterally spaced in each row and in lengthwise non-overlapping relation in adjoining rows, the rotary disk elements of one or more of said rows being integrally formed as a structural unit including intermediate spacer portions of reduced diameter together with supporting hubs at its opposite ends.

2. In a tape dispensing device, a housing having front and rear sections, the latter adapted to support a roll of tape to be dispensed, guide means for feeding the tape from said roll through a tape chute having a top opening and to deliver the tape forwardly from said front section of the housing, said guide means comprising a tape chute assembly unit including a bottom plate having a longitudinal slot formation, a separately formed top plate also having a slot formation opposite that in the bottom plate, said top plate being of less width than the bottom plate and having downturned side flanges for supporting and vertically spacing it above the latter and pro-

viding side guides for the tape to be advanced between the two plates as a feed throat, said plates having interlocked projections and receiving formations for attaching them in assembled relation, the front ends of the plates being vertically deflected in substantial parallelism for tape directing purposes and their rear ends being deflected away from each other to form a receiving mouth at the rear of the feed throat, 5 said rear deflected portion of the bottom plate adapted to aid in positioning the assembly unit on the dispenser frame with capacity for upward swinging about its rear portion and for bodily removal and the frame having laterally extending 10 positioning means for cooperation with said rear portion of the bottom plate to afford it said capacity, and tape-supporting and feeding means operatively disposed in the longitudinal slot formation of the bottom plate and cooperating with 15 said plate to present a tape chute flooring, said means including a plurality of rotatable roll elements extending transversely of the tape path and spaced lengthwise of said path in closely adjacent parallel relation to each other, said elements each having axially spaced portions of 20 relatively small diameter interposing disk-like parts of larger diameter adapted to have supporting and feeding contact with the under face of the tape.

TREVOR R. GAUTIER.
